METHOD AND APPARATUS FOR FORMING A
REFLECTOR SUPPORT ON AN INCANDESCENT LAMPRaymond W. Wengel, Rochester, N. Y., assignor
to Eastman Kodak Company, Rochester, N. Y.,
a corporation of New Jersey

Application September 13, 1939, Serial No. 294,726

15 Claims. (Cl. 176—3)

The present invention relates to a method and apparatus for forming a reflector support and a reflector on the glass envelope or bulb of a gas-filled incandescent lamp and more particularly to the use of the lamp filament for heating the glass to a plastic state and for heating the gases to expand a portion of the glass envelope.

The provision of reflector supports or reflectors on incandescent lamps has already been accomplished but for the most part the formation of the reflector support is accomplished at the time that the glass bulb is made and is accomplished by various procedures known to the glass-making or glass-blowing art.

The primary object of the present invention is the provision of a method and apparatus whereby a reflector support and a reflector may be respectively formed in and coated on the lamp after it has been manufactured.

A further object of the invention is a method and apparatus for utilizing heat from the lamp filament to heat the glass and to expand the gases in the lamp to deform a portion of the glass bulb.

Another object of the invention is the method and apparatus whereby the deformation of the glass bulb may be accomplished in such a manner that the reflecting surface coated thereon will reflect the image of the filament without interference with the lamp filament.

Still another object of the invention is to control the deformation of the glass bulb by a mold having a mold cavity with a polished surface.

A still further object of the invention is the use of a radiating means for re-radiating the heat from the lamp filament so as to heat only predetermined portions of the glass bulb.

Other and further objects of the invention will be suggested to those skilled in the art by the disclosure which follows.

The above and other objects of the invention are accomplished by a method for forming a reflector on the glass envelope of a gas-filled incandescent lamp having a filament by passing an electric current through the filament, heating the glass envelope by the heat from said filament, heating the gases in said glass envelope also by the heat from said filament to expand said gases and deform a portion of said glass envelope, and then covering the deformed portion of said glass envelope with a reflecting layer. The apparatus for forming the reflecting support on said glass envelope comprises a support for the lamp, a mold provided with a cavity having a polished surface and supported adjacent the envelope of the lamp, adjusting means for rela-

tively moving said support and lamp with respect to said mold, and a radiating member located adjacent said glass envelope for re-radiating the heat from said filament to heat said envelope and provided with openings arranged for observation of the filament image reflected from the polished surface of the mold cavity.

Reference is hereby made to the accompanying drawing wherein similar reference characters designate similar elements and wherein:

Fig. 1 is a side elevation in partial section of the apparatus for forming a reflector support on the glass bulb of an incandescent lamp according to the invention.

Fig. 2 is a plan view of such apparatus which is shown in Fig. 1.

Fig. 3 is a side elevation of an incandescent lamp which has been provided with a reflector according to the method and apparatus of the invention.

Fig. 4 is a wiring diagram of a modified circuit which may be used for energizing the lamp filament.

In the illustrated embodiment of the invention, a frame member 10 is provided with a guide-way 11. The incandescent lamp 12 is of conventional form such as used in motion picture projectors and comprises an elongated tubular glass envelope 13 fastened to a metal base 14. The filament 15 is supported by the stem 16 and wire 17 within said glass envelope 13 and is connected in a well known manner at one end to the metal base 14 and at the other end to the contact 18. The metal base 14 fits into a socket 19 from which extends a tube 20 and a cable 21.

The arrangements for connecting the lamp filament to a supply of energy may be made in several ways, for example, one leg 22 of cable 21 is connected directly to one side of an energy supply, while the other leg 23 of cable 21 may include a rheostat 24. Said rheostat 24 may comprise a contact arm 25 and a circular resistance element 26. When the contact arm 25 is in the position shown all of the resistance of rheostat 24 is in the lamp filament circuit and only a low filament current may be supplied. On the other hand, when contact arm 25 is in its other extreme position, little if any, of the resistance element will be in the circuit and a relatively high filament current will be passed through the lamp filament.

A mold 27 is provided with a concave cavity 28 which has a polished surface. Said mold 27 is supported adjacent the glass envelope 13 of the lamp 12 in any convenient manner such as by a bracket 29 having legs 30 and a cross mem-

ber 31 to which the mold 27 is fastened by bolts 32.

An adjusting means for relatively moving the lamp 12 with respect to the mold 27 may include several individual adjustments as shown or may comprise a universal movement type of support. The provision of vertical, transverse and longitudinal adjustments permits very accurate relative location of a lamp filament 15 with respect to the polished surface of the mold cavity 28 and is, therefore, preferred, although the adjusting means can be considerably simplified as by using a ball and socket support which will not be susceptible of extremely accurate adjustment.

The adjusting means shown comprises a slide 33 movable within guideway 11 by means of a screw 34 having a handle 35, having a head 36 rotatably engaging a plate 37 bolted to slide 33 and threaded through a plate 38 which is bolted to frame member 10.

20 A hollow standard 39 has a slide 40 movable in a transverse guideway 41 provided in slide 33. Transverse movement of slide 40 is obtained by a screw 42 having a handle 43, threaded through a plate 46 bolted to slide 33, and having a head 45 engaging but rotatable in a plate 44 which is bolted to the end of slide 40. Rotation of handle 43 and screw 42 will accomplish transverse movement of the slide 40 and standard 39 with respect to frame member 10.

30 Vertical adjustment of the lamp may be accomplished by a pinion gear 47 fastened to a shaft 48 which is journaled in lugs 49 of standard 39 and which carries a notched handle 50. The wall of hollow standard 39 is provided with an opening 51 through which pinion gear 47 extends into engagement with a rack portion 52 of a post 53. Obviously, rotation of handle 50 will raise or lower said post 53.

40 A clamp member 54 fits over the end of post 53, is provided with a slot 55, and has a bolt 56 for tightening one slotted end of clamp member 54 upon the post 53. In a similar manner the other end of clamp member 54 fits over tube 20, is provided with a slot 57 and carries a bolt 58 which may be tightened to fasten the other end of clamp member 54 to said tube 20.

50 In order to control or localize the heating of the glass envelope 13, a radiating member is located adjacent the glass envelope for re-radiating the heat from said filament selectively to heat the glass envelope 13. Such a radiating member may comprise a metal tube 59 fitted over the glass envelope 13 and provided with an opening 60 opposite the mold 27 and also provided with an opening 61 on the other side of the tube 59 for a purpose which will be later described. Although the radiating member as shown is in contact with the glass envelope 13, it is to be understood that such radiating member may be spaced from the glass envelope 13 and may be supported independently of the lamp 12.

60 In order to insure that the glass envelope 13 is not deformed at other points than those desired to be deformed, a cooling means is provided. Any cooling means that will accomplish selective cooling of the glass envelope is suitable. For purposes of illustration the cooling means may comprise a fan 62 attached to the frame member 10 and connected to blow air through 70 semi-flexible tubes 63 and 64. The tube 63 directs an air blast onto that portion of glass envelope 13 which is opposite the mold 27, while the tube 64 directs an air blast onto that portion of the glass envelope 13 which is adjacent the metal base 14. The circulation of the air at this point

75 may be further improved by the provision of a shield 65 fastened to socket 19.

For best lighting efficiency from a lamp carrying a reflector, it is necessary that the reflected image of the filament shall not interfere with or be shadowed by the lamp filament. The present method and apparatus are extremely well suited to the provision of the reflector so that such interference or decrease in efficiency does not occur. Since the mold cavity 28 has a polished surface, 10 the reflection of the filament image from said polished surface is the same as will be obtained from the reflecting layer which will be later placed upon the deformation in the glass envelope 13. Consequently, a low filament current is first 15 supplied to the lamp and the filament image reflected from the polished surface of mold cavity 28 is observed. In order to facilitate such observation, the radiating member or metal tube 59 is provided with the opening 61 and a reflecting 20 means is movable into the path of the light beam. Such reflecting means may comprise an inclined support 66 pivotally mounted to swing about a vertical axis by a bracket 67 attached to the support and pivoted by a pin 68 to a lug 69 on 25 one of legs 30. A mirror 70 is fastened by clips 71 to one side of support 66. This reflecting member may be swung into the position shown by the dot-dash lines of Fig. 1 for reflecting the direct image and reflected image of the filament 30 to a convenient place at one side of the apparatus or the reflecting means may be swung into an inoperative position as shown by the full lines in Figs. 1 and 2 so that the semi-flexible tube 63 35 may be placed adjacent the opening 61 of tube 59 for cooling of the portion of the glass envelope 13 which is adjacent said opening 61.

40 Since it is more desirable to adjust the lamp 12 and its filament 15 with respect to the polished surface of the mold cavity 28 while a low filament 45 current is passing through the lamp, it is preferable to provide a current control means or rheostat in the filament circuit but such current control or current reducing means is not absolutely necessary. The current control means may be 50 simplified in several ways, one of which is indicated in Fig. 4. One side of the filament 15 of lamp 12 is connected by a wire 22 to the supply 55 of energy, while the other side of filament 15 is connected by the wire 23 either directly to the other side of the energy supply or through a fixed 60 resistance 12 to the other side of said energy supply. A single-pole double-throw switch 73 in the position shown connects the filament directly to the current supply, whereas, when switch 73 is 65 moved to its other position, the fixed resistance 12 is connected in the filament circuit and the filament is maintained at a lesser brilliance for easier adjustment of the lamp with respect to the mold 27.

70 While one form of the apparatus for performing the method of the invention has been disclosed, it shall be understood that the method may also be accomplished with other forms of apparatus.

75 The procedure for performing the invention will now be reviewed. Basically, the method of the invention is accomplished by merely passing through the lamp a filament current sufficiently high to heat the glass envelope to plasticity and to expand the gases in the lamp for deformation 80 of a portion of the glass envelope. The deformation of the glass bulb or envelope may be irregular unless mechanical control is exerted over the molten glass. Consequently, the mold 27 is preferably employed and the concave cavity 28 in the 85

mold is formed so that the deformed portion of the glass envelope is a curved or spherical surface having its center at the lamp filament.

It has been found that the heat from the filament may be more efficiently utilized after a radiating means is placed adjacent the glass envelope to receive the intense radiant energy from the filament and re-radiate it to the glass bulb. Also in this manner selected portions of the glass bulb may be heated to higher temperatures to promote the deformation thereof by the expanding gases in the bulb. Obviously, the selective heating of portions of the glass bulb may be further controlled by air blasts which are arranged so as to be directed against any portions of the bulb to maintain the same at a lower temperature.

One outstanding feature of the present invention is that the location of the reflector support or reflecting layer applied thereto may be accurately controlled by the use of the forming element. In other words, the polished surface of the mold for the deformed portion of the bulb acts as a reflector during adjustment of the incandescent lamp with respect to the mold. Preferably, a low filament current is first supplied to the filament 15 either by use of a rheostat as shown in Fig. 1 or a switch and fixed resistance as indicated in Fig. 4. The operator, subjected to little or no blinding from the light, is able to observe the filament and its image as reflected from the polished surface of cavity 28 and to adjust any or all of the handles 35, 43 or 50 until the reflected image of the filament does not overlap or coincide with the actual filament. In the case of spaced filaments as commonly used, the reflected images of the filament sections come between such sections so that there is apparently a solid mass of incandescent filament.

After such adjusting operations have been performed the mirror 10 is moved out of position from beneath the lamp 12 and mold 27, the semi-flexible tubes 63 and 64 for the air blast are arranged as desired and the current control means is moved so that a high filament current passes through said filament 15. As above explained, the heat from the filament is re-radiated from the metal tube 59 and portions of the glass envelope 13, particularly around the opening 69 and tube 59, are heated to a plastic condition, the air blast from tubes 63 and 64 maintaining the neck of envelope 13 and the portion adjacent opening 61 in a relatively cool condition.

Finally, the portions of the glass envelope and the gases in the lamp 12 attain a temperature such that the gases expand to deform the glass envelope 13 and to force it onto the cavity 28 of mold 27. In this manner the deformed or bulged portion of the glass envelope conforms precisely to the polished surface of mold cavity 28 and a reflector support is provided directly in the glass envelope 13 of the lamp 12.

The reflecting layer on the deformed portion of the glass envelope may be provided in any of the several ways now known for forming mirrors or reflecting surfaces on glass. For instance, aluminum or other metal may be sprayed onto the glass envelope, preferably while its deformed portion is still hot. The aluminum may be sprayed by the Schoop process or silver may be deposited on such deformed portion of the glass bulb by means of the Brasher process. Furthermore, if desired, the reflecting layer may then be covered by a suitable protective coating so that

the reflecting surface will not become scratched or marred.

One great advantage of providing a reflecting portion directly on an incandescent lamp is that each time that a lamp is changed a new mirror is brought into use. Thus deterioration of the lamp mirror is limited to the life of a single lamp and does not continue throughout the life of the apparatus, such as a motion picture projector and during the use of several lamps.

Since many variations of the present invention are possible, the scope of the invention is to be determined by the claims which follow.

Having now particularly described my invention what I desire to secure by Letters Patent of the United States and what I claim is:

1. A method for forming a reflector on the glass envelope of a gas-filled incandescent lamp having a filament, which comprises passing an electric current through said filament, heating said glass envelope by the heat from said filament, heating the gases in said glass envelope also by the heat from said filament to expand said gases and deform a portion of said glass envelope, and covering the deformed portion of said glass envelope with a reflecting layer.

2. A method for forming a reflector on the glass envelope of a gas-filled incandescent lamp having a filament, which comprises passing an electric current through said filament, heating a portion of said glass envelope to a plastic condition by the heat from said filament, heating the gases in said glass envelope also by the heat from said filament to expand said gases and said heated portion of said glass envelope, and covering the expanded portion of said glass envelope with a reflecting layer having a reflecting surface facing said filament.

3. A method for forming a reflector on the glass envelope of a gas-filled incandescent lamp having a filament, which comprises passing an electric current through said filament, heating a portion of said envelope to a plastic condition by the heat from said filament, cooling a portion of said envelope to prevent deformation thereof, heating the gases in said glass envelope also by the heat from said filament to expand said gases and said heated portion of said glass envelope, and covering the expanded portion of said glass envelope with a reflecting layer having a reflecting surface facing said filament.

4. A method for forming a reflector on the glass envelope of a gas-filled incandescent lamp having a filament, which comprises passing an electric current through said filament, selectively reradiating the heat from said filament to heat a portion of said glass envelope to a plastic condition, heating the gases in said envelope by the heat from said filament to expand said gases and the heated portion of said glass envelope, and coating a reflecting layer onto the expanded portion of said glass envelope.

5. A method for forming a reflector on the glass envelope of a gas-filled incandescent lamp having a filament, which comprises passing an electric current through said filament, selectively reradiating the heat from said filament to heat a portion of said glass envelope to a plastic condition, heating the gases in said envelope by the heat from said filament to expand said gases and said heated portion of said glass envelope, mechanically controlling the expansion of said heated portion of said glass envelope, and coating a reflecting layer onto the expanded portion of said glass envelope.

6. A method for forming a reflector on the glass envelope of a gas-filled incandescent lamp having a filament, which comprises passing an electric current through said filament, selectively reradiating the heat from said filament to heat a portion of said glass envelope to a plastic condition, heating the gases in said envelope by the heat from said filament to expand said gases and said heated portion of said glass envelope, mechanically controlling the expansion of said heated portion of said glass envelope to form a spherical surface with its center of curvature at said filament, and coating said spherical surface with a reflecting layer having a reflecting surface facing said filament.
7. A method for forming a reflector on the glass envelope of a gas-filled incandescent lamp having a filament, which comprises passing an electric current through said filament, selectively re-radiating the heat from said filament to heat a portion of said glass envelope to a plastic condition, cooling a portion of said envelope to prevent deformation thereof, heating the gases in said envelope by the heat from said filament to expand said gases and said heated portion of said glass envelope, mechanically controlling the expansion of said heated portion of said glass envelope, and coating a reflecting layer onto the expanded portion of said glass envelope.
8. A method for forming a reflector support on the glass envelope of a gas-filled incandescent lamp having a filament, which comprises passing a relatively low current through said filament, reflecting an image of said filament from a surface complementary to that desired for the reflector support, passing a relatively high current through said filament, heating said glass envelope by the heat from the high filament current, and heating the gases in said glass envelope also by the heat from said high filament current to expand said gases and a portion of the glass envelope into contact with said complementary surface.
9. An apparatus for forming a reflector support on the glass envelope of an incandescent lamp having a filament, comprising a support for said lamp, means for connecting the filament of said lamp to a supply of energy, a mold provided with a cavity having a polished surface and supported adjacent the envelope of said lamp, adjusting means for relatively moving said support and lamp with respect to said mold, and a radiating member located adjacent said glass envelope for re-radiating the heat from said filament to heat said envelope and provided with openings arranged for observation of the filament image reflected from the polished surface of the mold cavity.
10. An apparatus for forming a reflector support on the glass bulb of an incandescent lamp having a filament, comprising a frame, a support member for said lamp, means for connecting the filament thereof to a supply of energy, a mold member provided with a cavity having a polished surface and supported adjacent the glass bulb of said lamp, and adjusting means between said frame and one of said members and for moving said lamp relatively of said mold member whereby the filament image reflected from the polished surface of the mold cavity can be adjusted with respect to the lamp filament.
11. An apparatus for forming a reflector support on the glass envelope of an incandescent lamp having a filament, comprising a support for said lamp, means for connecting the filament of said lamp to a supply of energy, a mold provided with a cavity and supported adjacent the envelope of said lamp, and a radiating member located adjacent said lamp for selectively re-radiating the heat from said filament to heat said envelope adjacent said mold whereby the gases in said lamp expand to bulge a portion of said envelope into the cavity of said mold.
12. An apparatus for forming a reflector support on the glass envelope of an incandescent lamp having a filament, comprising a support for said lamp, means for connecting the filament of said lamp to a supply of energy, a mold provided with a cavity and supported adjacent the envelope of said lamp, a radiating member located adjacent said lamp for re-radiating the heat from said filament to heat said envelope adjacent said mold, and cooling means arranged to cool portions of said glass envelope and prevent their deformation by the gases under pressure in said envelope.
13. An apparatus for forming a reflector support on the glass envelope of an incandescent lamp having a filament, comprising a support for said lamp, a lamp circuit including the lamp filament and a current control for a low filament current and a high filament current, a mold provided with a cavity having a polished surface and supported adjacent the envelope of said lamp, adjusting means for relatively moving said support and lamp with respect to said mold during a low filament current and for adjusting the filament image reflected from the mold cavity with respect to the lamp filament, and a radiating member located adjacent said glass envelope for re-radiating the heat from said filament when carrying a high filament current to heat said envelope whereby the gases in said lamp expand to bulge a heated portion of said envelope into the cavity of said mold.
14. An apparatus for forming a reflector support on the glass envelope of an incandescent lamp having a filament, comprising a support for said lamp, means for connecting the filament of said lamp to a supply of energy, a mold provided with a cavity and supported adjacent the envelope of said lamp, a radiating member located adjacent said lamp for selectively re-radiating the heat from said filament to heat selected portions of said envelope, and a cooling means circulating air over other portions of said envelope which are not to be deformed.
15. An apparatus for forming a reflector support on the glass envelope of an incandescent lamp having a filament, comprising a support for said lamp, means for connecting the filament of said lamp to a supply of energy, a mold provided with a cavity and supported adjacent the envelope of said lamp, a radiating member located adjacent said lamp for selectively re-radiating the heat from said filament to heat a selected portion of said envelope, an air impelling means, and semi-flexible conduits for directing air from said air impelling means onto portions of said envelope not to be deformed.

RAYMOND W. WENGEL.
